DESIGN FOR A SERVING DISH

Kenneth E. Baker, Fremont, Mich., assignor to Gerber Products Company, Fremont, Mich.

Application November 25, 1938, Serial No. 81,356

Term of patent 14 years

To all whom it may concern:

Be it known that I, Kenneth E. Baker, a citizen of the United States, residing at Fremont, Michigan, have invented a new, original, and ornamental Design for a Serving Dish, of which the following is a specification, reference being had to the accompanying drawing, forming a part thereof.

I claim:

The ornamental design for a serving dish, substantially as shown.

KENNETH E. BAKER.
